UNITED STATES PATENT OFFICE.

JAMES SAMUEL JONES, OF HARRISON, ARKANSAS.

SYRUP-PITCHER.

1,024,786.

Specification of Letters Patent. Patented Apr. 30, 1912.

Application filed April 29, 1911. Serial No. 624,231.

To all whom it may concern:

Be it known that I, JAMES S. JONES, a citizen of the United States, residing at Harrison, in the county of Boone and State of Arkansas, have invented a new and useful Syrup-Pitcher, of which the following is a specification.

This invention relates to syrup pitchers and has for its object to provide certain novel improvements in devices of this character.

This invention resides in the construction and arrangement of parts as hereinafter described and pointed out in the appended 15 claims, the invention being illustrated in the accompanying drawings, wherein similar reference characters indicate similar parts, and wherein—

Figure 1 is a central vertical sectional view of the pitcher. Fig. 2 is a side elevation thereof with the cap removed. Fig. 3 is a fragmental view in elevation. Fig. 4 is a perspective view of the parts illustrated in Fig. 3. Fig. 5 is a detail in section.

Referring specifically to the drawings, the numeral 5 designates a vessel, preferably of glass, which merges or blends at its upper end into the neck 7, the said neck having the edge thereof beaded or thickened as designated at 9. A metallic jacket 8 encompasses the neck 7, having the lower end thereof fitting on the annular shoulder 6 of the vessel 5, and the said jacket rises above the mouth of the neck 7, having an outwardly directed portion 10 above the mouth of the neck forming the outwardly extending flange 10 and forming the drip cup 11 above the said flange.

A cylindrical spout 12 is arranged within 40 the drip cup 11 having the upper end thereof protruding above the drip cup and having the lower end thereof depending into the mouth of the neck 7. This spout 12 is provided with an exterior horizontal flange 45 13 slightly above the lower end thereof which seats or rests on the flange 10 of the jacket 8. A ring 15 is secured within the lower end of the spout 12, by soldering or otherwise, and the lower end thereof projects beyond the said spout and is flared outwardly as designated at 14 below the bead 9. A suitable filling of sealing material is arranged in the space between the bead 9 and the flared portion 14 of the ring 55 15, which is inserted therein in a soft or

plastic state as the members are put together and upon hardening presents a solid filling between the bead 9 and the flared portion 14 of the ring 15 which is secured to the spout 12 for preventing the spout from being 60 removed from the neck 7, and the flange 13 of the spout seating on the flange 10 of the jacket 8 also prevents the said jacket from being removed. The filling above referred to may be of any suitable composition, preferably of plaster-of-Paris. The spout 12 is provided with an elongated upright slot 24 therein above the flange 13.

A cover 30 is provided for the spout 12 which has a fork 33 depending from one 70 edge thereof over the side of the spout 12 between a pair of ears 32 projecting from the said spout, the said fork 33 being hinged to the said ears as designated at 31 by a pin 38 which extends through the said ears 75 and fork. A coiled spring 37 is arranged on the pin 38 between the arms of the fork 33 and has one end thereof secured to the said pin and the other end bearing against the said fork to tend to hold the cover 30 80 against the spout 12. The pin 38 is provided on one end with a square head which fits in a square socket in one of the ears 32 serving as a means to hold the said pin in its adjusted position. Thus by sliding the 85 pin outwardly slightly the head thereof may be disengaged from the socket in the corresponding ear whereupon the said pin may be revolved to increase or decrease the tension of the spring 37. A wire loop 36 is 90 pivotally hung from the lower end of the ears 32 and is adapted to engage a hook 35 extending from the thumb piece 34 of the cover 30 upon the cover being swung open thus retaining the cover in open position. 95

A meshed wire strainer 22 is secured at its periphery within the drip cup above the slot 24 in the spout and has the inner edge thereof spaced slightly from the said spout, thus permitting the drippings to run down 100 the sides of the spout between the said spout and the inner edge of the strainer into the drip cup. This prevents the strainer from becoming plugged up by the syrup and permits the syrup to run down into the drip cup, the entrance of insects or other foreign matter into the drip cup being prevented by the said strainer.

A cap 20 fits over the cover 30 and the upper end of the spout 12 and fits within 110

the upper end of the drip cup 11 at its lower end thus inclosing the cover 30 and the spout.

A handle 17 is secured to the metal jacket 5 8 at its lower end and to the drip cup 11 at its upper end.

In use, the syrup is poured from the vessel in the ordinary manner, the cap 20 having been first removed and the cover 30 10 swung open.

The spout 12 protruding above the drip cup permits the syrup to be readily poured out and when the pitcher is rightened the drippings on the outside of the spout run 15 down into the drip cup and back into the vessel, the strainer preventing insects or other foreign objects from entering into the drip cup.

What is claimed is:—

- 20 1. In a syrup pitcher, a vessel having a neck, a jacket encompassing the neck and extending above the mouth thereof, the said jacket being extended outwardly at the mouth of the neck to form a flange and the 25 portion thereof above the said flange forming a drip cup, a cylindrical spout arranged within the drip cup and having a flange resting on the said flange of the jacket and having a slot therein above the said flange, 30 a strainer secured at its periphery to the

drip cup above the slot in the spout and having the inner edge thereof spaced from the said spout, a cover for the spout, and a cap seating on the upper end of the drip cup to inclose the said cover and the spout. 35

2. In a syrup pitcher, the combination of a spout having a pair of ears projecting from one side thereof, one of the said ears having a non-circular socket therein, a cover for the spout having a fork depending from the edge thereof between the said ears, a pin passing through the said ears and the said fork and having a non-circular head adapted to engage in the non-circular socket, and a coiled spring arranged on the said pin 40 between the arms of the fork having one end thereof secured to the said pin and the other end thereof bearing against the said fork, whereby upon the pin being slid outwardly the head thereof may be disengaged 45 from the said socket to permit the pin to be rotated to increase or decrease the tension of the spring.

In testimony that I claim the foregoing as my own, I have hereto affixed my signature 50 in the presence of two witnesses.

JAMES SAMUEL JONES.
